No. 818,544.

PATENTED APR. 24, 1906.

R. LOHDA.

ANTI TIP OVER DEVICE FOR BOB SLEIGHS.

APPLICATION FILED MAY 8, 1905.

UNITED STATES PATENT OFFICE.

ROBERT LOHDA, OF FORT ATKINSON, WISCONSIN, ASSIGNOR TO
NORTHWESTERN MANUFACTURING COMPANY, OF FORT ATKIN-
SON, WISCONSIN, A CORPORATION OF WISCONSIN.

ANTITIP-OVER DEVICE FOR BOB-SLEIGHS.

No. 818,544.

Specification of Letters Patent.

Patented April 24, 1906.

Application filed May 8, 1905. Serial No. 259,260.

To all whom it may concern:

Be it known that I, ROBERT LOHDA, residing in Fort Atkinson, in the county of Jefferson and State of Wisconsin, have invented 5
new and useful Improvements in Antitip-
Over Devices for Bob-Sleighs, of which the
following is a description, reference being had
to the accompanying drawings, which are a
part of this specification.

10 My invention has relation to an antitip-
over device for bob-sleighs.

In the form of sleighs known as "bob-
sleighs" the front and rear bobs are loosely
jointed together, and in use if the front bob is
15 turned at an angle to the rear bob the front
bolster is caused to assume a position across
the longitudinal plane of the front support-
ing-bar of the front bob, and if there is any
excess weight on the projecting end of the
20 front bolster the said bolster is caused to tilt,
and this tilting is frequently communicated
to the front ends of the runners and to the
tongue, causing an upward tilting of these
parts.

25 It is the primary object of my invention to
provide an improved construction of device
to prevent the above-pointed-out objections;
and with this object in view the invention
30 consists of the devices and parts or their
equivalents, as hereinafter set forth.

In the accompanying drawings, Figure 1 is
a plan view of my invention, showing its ap-
plication to the front bob of an ordinary form
35 of bob-sleigh. Fig. 2 is a longitudinal sec-
tion on the line 2 2 of Fig. 1. Fig. 3 is a detail
view of the circle looking against the
rear portion of said circle, and Fig. 4 is a view
40 of a fragment of the front cross-bar and of
the rear end of the tongue mortised or se-
cured to said bar.

The drawings illustrate a front bob of or-
dinary construction, consisting of runners 5
5, the knees or brackets 6 6, bolted to the run-
ners, and the transverse supporting-bar 7,
45 which is bolted at its opposite ends to the
knees or brackets. The front ends of the
runners are connected, as usual, by means of
the front cross-bar 8, and to which bar the
rear end of the tongue 9 is connected.

50 Referring particularly to my improve-
ments, the numeral 10 indicates a circle, con-
sisting of a complete circular band or ring.
This circle is rigidly secured to the transverse

supporting-bar, preferably by means of an-
gular plates 11 11, the horizontal portions of 55
said plates being bolted to the supporting-
bar and passing beneath the circle, the up-
right portions of said plates lying adjacent to
diametrically opposite points of the inner
face of the circle and secured thereto by 60
means of rivets. In this manner the circle is
firmly secured against lateral movement
upon the transverse supporting-bar 7. The
said transverse supporting-bar is provided
centrally with an opening 12 for the king- 65
bolt. (Not shown.) Loosely mounted upon
the upper end of this king-bolt is the turn-
able member or fifth-wheel, (not shown,)
which is carried at the forward end of the
70 reach of the rear bob.

The rear end of the tongue 9 preferably
projects slightly beyond the front connecting-
bar 8, and this projecting end has extending
upwardly from its upper side an eye 13, said
eye being preferably formed at the upper end 75
of an eyebolt 14, which bolt passes through
the tongue and has its lower end threaded to
receive a nut 15, which is turned up tightly
against the under side of the tongue. The
eyebolt may pass through a washer 16, and 80
this washer may either bear directly against
the top surface of the tongue or against a
wear-plate 17, interposed between the washer
and the top surface of the tongue. The eye
13 extends sufficiently high to receive loosely 85
therethrough the forward slightly-upturned
end of a straight finger 18. This finger is
split or diverged from a point a suitable dis-
tance back of its forward end to form two
members 19 19, which extend rearwardly and 90
lie adjacent and conform to the arc of the cir-
cle 10 and are rigid therewith by means of
rivets or otherwise.

From the construction described it will be
seen that I provide a simple and convenient 95
device for preventing tilting of the front bol-
ster and the uptilting of the tongue and for-
ward ends of the runners, this being accom-
plished by reason of the fact that the finger
18 passes loosely through, and therefore has 100
play in, the eye 13, which has the effect of re-
sisting the tendency of the tilting referred to,
and which tilting may be due to excess
weight exerted on the end of the front bolster
when the front bob is turned at an angle to 105
said bolster or due to other causes.

By referring to Fig. 2 it will be noticed that by extending the end of the tongue rearward I am enabled to use a short finger 18 of simple construction and that the tops of the circle 10 and arms 19 are maintained in a horizontal plane, so that a broad extended support for the load is provided and the front ends of the runners may rise over inequalities or obstructions without causing the tongue and finger to bind and injure one or the other. Were the finger bent down to engage under the cross-bar, the finger would be weaker, the cost greater, and a downward movement of the rear end of the tongue would be apt to break the finger. Furthermore, the front cross-bar 8 is left intact, so that the strength of the same is not impaired.

What I claim as my invention is—

In a sleigh, the combination of the runners, a cross-bar connecting the front ends of the 20 runners, a tongue secured upon said cross-bar and projecting slightly rearward thereof, an eye secured in the rear end of the tongue and rising therefrom, a frame supported by the runners, and a finger projecting forward 25 from said frame and having its front end upturned and projecting through and playing loosely in the eye rising from the tongue.

In testimony whereof I affix my signature in presence of two witnesses.

ROBERT LOHDA.
